ACCOUNTING MACHINE

Ansgar F. Sturm, Staten Island, N. Y., assignor to
 Mergenthaler Linotype Company, a corporation
 of New York

Application July 25, 1936, Serial No. 92,539

20 Claims. (Cl. 235—60)

This invention relates to accounting machines of the general organization disclosed in my Patent No. 2,052,905, filed July 29, 1932, and issued September 1, 1936 (of which the instant application is a continuation in part), wherein there are provided a plurality of accumulators capable upon selection, of independent association with a plurality of common actuating rack bars through which amounts may be entered into the accumulators by addition or subtraction, and through which also accumulators may be selectively associated with printing mechanism for printing amounts registered therein, and where there is also provided means for transferring an amount registered in one accumulator to a second accumulator by addition and to a third accumulator by subtraction in one cycle of operation of the machine.

More particularly, the invention is directed to a carrying mechanism which is common to all of the accumulators, and which operates both for addition and subtraction. The carrying mechanism operates through the actuating rack bars, the bars being movable an additional space in either direction, depending upon whether an addition or a subtraction carry-over is required. In some machines of this class, the actuating rack bars have a range of movement in one direction only of nine spaces and one additional space for carrying, whereas in the instant machine, the rack bars have a similar range of movement in both directions for the same purpose.

As a result of this construction, the machine is capable of adding in one accumulator and subtracting in another accumulator in one cycle of operation of the machine. Furthermore, it permits the use of accumulators having a single set of digit wheels, engageable directly with the rack bars both for addition and subtraction, thus conserving space and affording a construction wherein the accumulators are visible to the operator.

Referring to the drawings:

Fig. 1 is a longitudinal vertical section through an accounting machine employing the present improvements and with the parts in normal position;

Fig. 2 is a partial horizontal section on line 2—2 of Fig. 1;

Fig. 3 is a detail, showing certain operating parts of the carrying mechanism during one phase of operation;

Fig. 4 is a partial longitudinal sectional view, showing the carrying mechanism just after a carrying operation in subtraction;

Fig. 5 is a partial vertical transverse section,

showing certain details of the carrying mechanism looking at the parts from the front;

Fig. 6 is a view, similar to Fig. 4, but showing the carrying mechanism during a total transfer operation and just prior to a carrying operation 5 in subtraction;

Fig. 7 is a view similar to Fig. 4, but showing the carrying mechanism just after a carrying operation in addition;

Fig. 8 is a view of a portion of the carrying 10 mechanism, showing the location of the rack bars after an operation in addition and where no carrying operation is to be effected;

Fig. 9 is a view of a portion of an accumulator and its cooperating rack bars, a portion of the 15 accumulator wheels and the rack bars being in section;

Fig. 10 is a view similar to Fig. 6, but with the parts controlled from the keyboard instead of from an accumulator during a total transfer 20 operation; and

Fig. 11 is a vertical transverse section on line 11—11 of Fig. 1.

The invention has been illustrated as applied to the accounting machine disclosed in the Sturm 25 patent before alluded to, and to which reference may be had for a more detailed description of the parts and the actuating mechanisms.

Briefly, the machine includes a series of accumulators A, B, C, etc., arranged one behind the 30 other in tandem relation between side frames D fixed to the base plate of the machine (Figs. 1 and 5), and which in their normal position are raised clear of a set of fore-and-aft reciprocable rack bars E positioned directly therebeneath. 35 The accumulators consist each of a plurality of rotatable digit wheels F (Figs. 1 and 9) mounted on a common shaft F¹ and having their peripheries divided into ten spaces, numbered respectively from 1 to 9 and zero, in a counterclockwise direction, looking at the machine from the right.

As shown best in Fig. 9, each digit wheel F includes a pair of thin discs f secured at its opposite faces, and also a small gear wheel f¹, by means of which it is rotated. The disc f at the right is provided with an arresting tooth or tit f² for locating the digit wheel in the zero position, and the other disc at the left with a corresponding tooth or tit f³ which controls the carrying operation from one digit wheel to another. The 40 accumulators are equipped each with a pair of selection keys (not shown), one for selecting an accumulator for operation in addition and the other for selecting an accumulator for operation in subtraction, as well as with a total key for 45

55

clearing the accumulator and printing the amount registered therein. By depressing the subtraction key of a selected accumulator, the latter will, after a cycle of operation is inaugurated, be 5 engaged with the underlying rack bars E of the actuating mechanism before they are moved rearwardly, to effect the subtraction operation; whereas, by depressing the add key of a selected 10 accumulator, such accumulator will be engaged with the rack bars just before they start their return movement, to effect an operation in addition. The selection keys and total key, just referred to, together with the mechanisms for 15 effecting the operations indicated, are fully disclosed in the Sturm Patent No. 2,052,905, which is made a part hereof by reference.

The rack bars E extend fore-and-aft of the machine and are displaced rearwardly and returned once during each machine cycle of operation. The distance through which the rack bars are displaced in any cycle determines the extent of rotation of the accumulator wheels engaged therewith. The displacement of the rack bars is controlled from a keyboard (not 20 shown) having a set of ten digit keys, which are numbered 1 to 9 and zero, respectively, and when depressed raise corresponding stop fingers G of a stop carriage G¹ into the path of the rack bars to limit their rearward movement (see Figs. 25 1 and 10). A more detailed description of the stop carriage may be found in my patent, previously alluded to.

The printing mechanism is arranged at the rear of the rack bars E and includes a set of 30 vertical slides or type bars H which are movable individually upwardly and downwardly to locate one or another of a series of type elements H¹ into and out of operative relation with a platen or printing roll H². The upward movements of the bars H are effected by pull springs H³ and 35 are controlled by the rearward movement of the rack bars E through intermediate gear sets H⁴ and a series of auxiliary rack bars H⁵ supported on fixed transverse shafts H⁶ and H⁷. If a main rack bar E is allowed to move, say eight spaces, 40 into contact with the eight stop of the carriage G¹, the associated auxiliary bar H⁵ is caused to follow it by the pull of its associated spring H³, so that the vertical type bar H will rise a corresponding number of spaces. Actually, the auxiliary rack bar H⁵ will move one space more than 45 its associated rack bar E, in order to locate the first or zero type element H¹ in active position. The additional space is required to allow the 50 rack bars to move the extra space beyond normal position in the return direction for carrying in addition. As far as the active spaces are concerned however, the movement of the bar H⁵ will correspond to the movement of its associated rack bar E. The mechanism for setting the type bars H, under the control of the main rack bars E, is more fully described in my previously mentioned patent, to which reference may 55 be had.

60 After the type bars have been located in printing position, a series of hammer elements I will be moved from the position shown in solid lines in Fig. 1 to the position shown in dotted lines, wherein they cooperate with the type elements 65 in printing position to print the number.

The number registered in any accumulator may also be printed, in which case, of course, the stop carriage will not be active. In printing from an accumulator, the letter is, upon selection by its total key, lowered into engagement 70

with the rack bars E which will be moved rearwardly under the control of the accumulator until the latter registers zero, as determined by the engagement of the tip f² against a stop bar N when the accumulator wheels have reached the zero position, and this movement of the rack bars E will control the operation of the printing bars H in the manner previously described.

The accumulator actuating mechanism is common to all three accumulators, A, B and C and is adapted to function at different stages during each machine cycle to rotate the digit wheels of selected accumulators in one direction for addition and in the other direction for subtraction. This mechanism is supported between the upright side frames D and includes the series of main rack bars E which are equal in number to the digit wheels in each accumulator. As shown in Fig. 1, the rack bars are formed in their upper edges with a series of teeth E¹, and in their lower edges with a series of similar teeth E². At their front and rear ends, the bars E are formed with slots E³ and E⁴ (Fig. 7), by means of which they are suitably supported and guided on annularly grooved shafts E⁵ and E⁶. Near the front end, each rack bar is cut away, as at E⁷, to provide clearance for the stop carriage G¹ (Fig. 7), and at this end it terminates in a portion having three surfaces e, e¹, e², the surface e being presented at the front end of the cut-away portion E⁷ and adapted under certain conditions to engage one or another of the stops G (when raised) when the rack bar E is moved rearwardly so as to arrest the latter, the surfaces e¹ and e² being presented at the front end of each rack bar E for a purpose hereinafter to be described. The rack bars E, that is, all except the one at the extreme right of the machine, are provided each with an arm K³⁰ (Fig. 1) pivotally mounted on the rack bar adjacent the rear of the cut-away portion E⁷ and presenting, at its front end, an interponent K²⁹ positioned adjacent and immediately at the rear of the surface e. The dimension of the interponent in a direction lengthwise of the rack bar is equivalent to one space of movement of the latter. When an item is entered in an accumulator by means of the keyboard, the rack bars are arrested in their rearward movement by the engagement of the interponents with the selected stops G, except when carrying in subtraction is required. When subtraction carrying from one order to the next higher order is necessary, the interponent associated with the rack bar of the latter order is raised, permitting such rack bar to move an additional space rearwardly or until the corresponding surface e engages the active stop bar G. The manner of operation of the interponents will be described more in detail later on.

Each of the bars E is actuated by a set of reduction gears E⁸ and E¹⁰, the gears E¹⁰ meshing with the teeth E² on the lower edge of the actuating bars, and the gears E⁸ with a set of subsidiary rack bars E¹¹, the latter, as shown in Fig. 1, being arranged below the bars E and mounted for a limited fore-and-aft movement. At their front ends, the racks E¹¹ are guided in a fixed comb plate E¹² extending transversely between the side frames, and at their rear ends are supported upon a rod E¹³, which is likewise mounted in the side frames. Depending from the rear ends of the racks E¹¹ are projections E¹⁴ to which are attached tension springs E¹⁵ anchored at their front ends to a bar E¹⁶ ex-

tending crosswise of the machine and mounted in a pair of frame members E^{17} , located one at each side of the machine. The members E^{17} are suitably guided for a limited fore-and-aft 5 movement and are loosely connected at their rear ends, as at E^{18} , to a pair of vertically disposed actuating arms E^{19} depending from a rock shaft E^{20} which is controlled from the main shaft M of the machine. An additional 10 sliding member E^{21} (Figs. 1 and 6) is connected to each of the subsidiary racks E^{11} by a pair of pin and slot connections e^2 .

Both the racks E^{11} and sliding members E^{21} have projections E^{22} and E^{23} , respectively, 15 which are connected together by strong pull springs E^{24} . The movement of the auxiliary rack bars E^{11} is controlled by a bail rod E^{25} , common to all of said bars and connected to the actuating arms E^{19} through the medium of 20 angular supporting arms E^{26} , which receive support from the sliding frame members E^{17} by means of pin and slot connections E^{27} and E^{28} . According to this arrangement, when the parts 25 are at rest, i. e., in their normal state, the rack bars E will at their front ends and at the surfaces e^1 , engage a bail J extending crosswise of the machine, being held resiliently in this position by the bail E^{25} acting through the sliding members E^{21} , the springs E^{24} , the subsidiary 30 rack bars E^{11} , and the intermediate gears E^9 and E^{10} .

When the rock shaft E^{20} is turned in a clockwise direction to swing the arms E^{19} forwardly to the dotted line position shown in Fig. 1, the tension of the springs E^{24} is first neutralized and the springs E^{15} then placed under tension, so as to pull the subsidiary rack bars E^{11} forwardly and, through the gears E^9 and E^{10} , force the actuating rack bars E rearwardly until they are arrested by the engagement of the interponents K^{29} with the stops G in the carriage G^1 , or if 40 an accumulator is engaged for totaling, by the tits f^2 engaging the total stop bar N . On the other hand, when the rock shaft E^{20} is turned 45 in a counterclockwise direction to swing the arms E^{19} rearwardly from the dotted line to the solid line position shown in Fig. 1, the bail rod E will, through its engagement with the sliding members E^{21} , push the auxiliary bars E^{11} also rearwardly 50 and finally, i. e. at the end of the return stroke of the arms E^{19} , will stretch the springs E^{24} . This rearward movement of the auxiliary rack bars E^{11} will, through the intermediate gear connections, move the main rack bars E forwardly 55 and return them to normal position.

During the operation of the rack bars E , as just described, an accumulator selected for subtraction will be engaged therewith and rotated thereby during the first phase of the machine 60 cycle, i. e., when the rack bars E move rearwardly; whereas, an accumulator selected for addition will be engaged with the rack bars and rotated thereby during the second phase of the machine cycle, i. e., when the rack bars move forwardly to their normal positions. In performing 65 these mathematical operations, it is often necessary to carry over from one digit wheel in an accumulator into another digit wheel, as for instance, when the addition of several digits in 70 one wheel exceeds nine, or when the digit of the subtrahend is greater than its corresponding digit in the minuend. A carrying mechanism therefore, is provided, which, according to the present invention, is not only common to a plurality of 75 sets of accumulators, but is also capable of effect-

ing carrying both for addition and subtraction in selected accumulators in one cycle of operation of the machine.

As before stated, the carrying operations in subtraction are adapted to take place at the 5 end of the rearward movement of the rack bars E and, in addition, at the end of the return movement of said rack bars, carrying being effected by providing for an additional movement of the rack bars in both directions, while the 10 accumulator in which the carrying operation is to take place is still engaged.

These operations, in the present instance, are accomplished through the medium of a set of links K extending in a direction fore-and-aft of 15 the machine and arranged for operation by the digit wheels of the accumulators. The links K condition for operation a corresponding set of vertical slides K^1 adapted to be raised and lowered twice during each cycle of the machine, 20 namely, after the rearward movement of the rack bars E , and again after the return movement of the rack bars. The operation of a given slide K^1 , as determined by one digit wheel of an 25 accumulator, will permit the rack bar E associated with the digit wheel of next higher order to move an additional space rearwardly or forwardly to effect carrying, depending upon whether the slide K^1 is raised at the end of the advance 30 stroke or during the return stroke of the rack bars E .

The links K (see Figs. 1, 5 and 9) are arranged alongside the respective rack bars E and supported on shafts E^5 and E^6 which extend transversely of the machine through curved slots K^2 35 and K^3 formed in said links. Each of the links K is provided at spaced intervals along its upper edge with lugs K^5 (one for each accumulator), by means of which it may be moved longitudinally in either direction and as permitted by the 40 slots K^2 and K^3 . These lugs in the normal position of the links are located directly below the axes of the respective accumulators A , B and C , so as to be disposed in the path of the tits or lugs f^3 of the individual accumulator wheels when 45 they are lowered into mesh with the teeth on the rack bars E , and the angular position of the tits f^3 is such that, when the accumulator wheels are turned clockwise as in addition, from 9 to zero, the corresponding links will be pushed forwardly (see Fig. 7), whereas when the accumulator wheels are turned counterclockwise as in subtraction, from zero to 9 , the corresponding links will be pushed rearwardly (see Figs. 4 and 10). 50

When the machine is at rest (Fig. 1), the links K are held in normal position and against accidental displacement (since their mounting is relatively sensitive in order to be capable of operation by the accumulator wheels) by an equalizing member K^6 , common to all of the links and arranged between a pair of vertical fingers K^7 rising from the upper edge of each of the links K near the front ends thereof. When the equalizing member K^6 is in its normal position, the lateral edges thereof engage the front and rear fingers K^7 of the links K . Just prior to the rearward movement of the rack bars E , however, the equalizing member K^6 is turned to the position shown in Fig. 3 to free the links K for movement 70 by the engaged accumulator and just after the carrying operation at the end of the rearward stroke of the rack bars E has been completed, the member K^6 is turned to normal position to restore the links K , and the same operations are 75

repeated just prior to and at the completion of the return movement of the rack bars E, the restoration of the links K being effected by the engagement of the equalizing member K⁶ with one or the other of the vertical fingers K⁷, according to the position of the links.

In order to effect the movement of the equalizing member K⁶, as just described, it is fastened at the left to a hub member K⁸ rotatably mounted 10 in the side frame D, and at the right to a similar hub member K⁹, likewise rotatably mounted in the frame D (see Fig. 5). The member K⁸ is operated by a gear segment K¹⁰ from an edge cam M¹ keyed to the main shaft M of the machine (see Figs. 2 and 3). Motion from the main shaft M is imparted to the segment K¹⁰ through a bell crank lever K¹¹ journaled on a fixed pivot K¹² at the rear of the machine and an intermediate connecting link K¹³, the latter 20 being provided near its front end with a short toothed portion K¹⁴ which meshes with the teeth on said segment. The bell crank is provided with a cam follower K¹⁵ which is constrained to track along the cam M¹ by a spring K¹⁶ secured at one end to said bell crank and anchored at its other end in a fixed part of the machine, and which at the same time tends to urge the connecting link K¹³ to its forward position.

30 When the main shaft M is at rest, the cam follower K¹⁵ is engaged with a high portion M² of the cam M¹ and the link K¹³ is held rearwardly against the tension of the spring K¹⁶ to locate the equalizing member K⁶ in its normal 35 position, wherein the links K are locked against movement (Fig. 1). However, as soon as the cam shaft M starts to revolve in the direction as indicated by the arrow (the high portion M² being comparatively short), the spring K¹⁶ is 40 allowed to pull the link K¹³ forwardly and, through the gear segment K¹⁰, turn the equalizing bar K⁶ to the position shown in Fig. 3, wherein the carrying links K are freed for operation by the pins j³ on the accumulator wheels.

45 After the carrying operation on the advance or rearward stroke of the rack bars E has been completed, the cam follower K¹⁵ will engage a high portion M³ of the cam M¹ and, through the intermediate devices previously mentioned, 50 rotate the equalizing member K⁶ to its normal position, thus restoring the links K. Immediately thereafter, and prior to the forward or return movement of the rack bars E, the roller K¹⁵ will ride off the high portion M³ of the cam 55 M¹ again to rotate the equalizing member K⁶ and release the links K in order that the parts will be in condition for carrying on the return stroke or in addition, and again at the end of the return stroke the links K will be restored 60 to normal position as the roller K¹⁵ rides up on the high portion M² of the cam M¹.

The movement of the rack bars E the additional distance of one space during both the advance as well as the return stroke in those 65 denominations in which carrying is to occur, is controlled from the vertical slides K¹, which in turn are controlled by the slides K associated respectively with the digit wheels of next lower order and which determines whether or not a 70 carrying operation is to take place.

The slides K¹ are guided at their lower ends in a fixed comb plate K¹⁷ and are urged upwardly by springs K¹⁸ anchored at their upper ends to a fixed bar K³⁴ and fastened at their lower ends 75 to a series of arms L¹² (corresponding in num-

ber to the slides K¹) which engage at their upper edges against protrusions K¹⁹ with which the slides are equipped. The arms L¹² are pivotally mounted at their front ends (Figs. 6 and 7) on a fixed cross bar L¹³ near the front of the machine and are guided in their movements by the comb plate K¹⁷ and at their front ends by an additional comb plate L¹⁴. The slides K¹, at their upper ends, are slotted to engage in annular recesses of a vertically movable cross bar 10 or bail K²⁰ which holds the slides in a normal depressed position against the tension of the springs K¹⁸. The bail K²⁰ is guided in the fixed framework of the machine and is connected by links K²¹ and a pair of actuating arms K²² to the 15 shaft E⁵, previously alluded to (see Fig. 3). The slides K¹ are provided with upstanding projections K²³ arranged directly beneath studs K⁴ formed on the links K at their forward ends. Twice during each cycle of the machine, the 20 bail K²⁰ rises and, when it does so, the slides K¹ would follow were it not for the fact that they are held downwardly by the studs K⁴ overlying the projections K²³, except in those denominations where the links K have been displaced 25 either forwardly or rearwardly by the rotation of their corresponding digit wheels from 9 to zero in addition or from zero to 9 in subtraction. Where the slides K¹ have been allowed to rise, they will permit an additional movement 30 of one space of the rack bar E in the next higher denomination, rearwardly if the rise is at the end of the rearward stroke of the rack bars or forwardly if the rise is at the end of the return stroke of the rack bars.

35 The bail K²⁰, and consequently the slides K¹, are held in their lower positions (Fig. 1) by a segmental disc K²⁷, concentric throughout a portion of its peripheral edge, and pinned to the hub member K⁸ (which operates the equalizing 40 member K⁶, see Fig. 5). The disc K²⁷ engages an antifriction roller K²⁸ mounted at the side of one of the actuating arms K²². As shown in Figs. 3 and 4, the disc K²⁷ is formed in its outer edge with a depression or recess k which is adapted at two predetermined portions of each cycle of operation and as permitted by corresponding low portions M⁴ and M⁵, formed in the cam M¹, to be brought into registry with the roller K²⁸, in order to allow the bail K²⁰ to rise under the 45 influence of a spring K³³ connected to the actuating arm K²² and anchored in a fixed part of the machine (Fig. 3).

50 It will be noted that the depression M⁴ in the cam M¹ is located just in advance of the high portion M³ thereof, which restores first the slides K¹ and then the links K to normal position at the end of the rearward movement of the rack bars; also that the depression M⁵ in said cam is located in advance of the high portion M² 55 thereof which restores the slides K¹ and the links K to normal position in the same sequence at the end of the return movement of the rack bars, and it is during the time that such low portions of the cam M¹ are active that the slides K¹, 60 which have been freed at a result of the displacement of the links K, are allowed to rise to permit the movement of the rack bars the additional space for carrying either in addition or subtraction.

65 The movement of the rack bars E the additional space on the rearward stroke to effect carrying in subtraction, is controlled from the slides K¹ through the medium of a series of bell crank levers L arranged beneath the rack bars 70 75

and provided one for each of said bars except the first (see Figs. 1 and 7). The levers L are pivotally mounted on a cross shaft L¹ extending transversely between a pair of arms L² pivotally mounted at their front ends on a fixed cross shaft L³, the arms L² being arranged one at each side of the machine and directly above the fore-and-aft frame members E¹⁷. The levers L are guided in a comb plate L⁴ extending transversely between the arms L², and their degree of movement is limited to one space of the rack bars by slots L¹⁵ in the comb plate E¹² which guides the subsidiary rack bars E¹¹. The levers L are held in their normal position at the front ends of the slots L¹⁵ by a corresponding series of springs L⁶ anchored at one end to depending lugs L⁷ on the levers and at their other ends to a cross bar L⁸ extending between the arms L² adjacent the rear ends thereof.

50 The arms L² are provided each with an anti-friction roller L⁹ and, when the frame members E¹⁷ are actuated forwardly to effect the rearward movement of the rack bars E for subtraction, in the manner previously described, a pair of cam surfaces L⁵ formed in the upper edges of said frame members E¹⁷ will engage the anti-friction rollers L⁹ and swing the arms L² upwardly, causing gear tooth-shaped projections L¹⁰ formed at the upper ends of the levers L to enter into one or another of the recesses between the teeth E² formed in the bottom edges of their associated rack bars E (see Fig. 6). This engagement of the carrying pawls L will take place after the rack bars E have come to rest, the range of movement of the frame members E¹⁷ being considerably more than that necessary to cause the rack bars E to traverse their full range of movement.

It will be understood that the force of the 40 springs E¹⁵, tending to urge the rack bars E rearwardly, is more than sufficient to overcome the tension of the springs L⁶ acting on the carrying pawls L, but the pawls L will prevent any rearward movement of the rack bars E when 45 they are engaged therewith due to the fact that they are held in their forward positions in the slots L¹⁵ by the arms L¹² which in turn are held downwardly by the slides K¹ and which have projections L¹¹ at their ends normally overlying forwardly extending arms L¹⁶ with which the pawls are equipped (see Fig. 6). However, when a slide K¹ is raised as a result of the displacement of the link K which controls it, through the operation of the engaged accumulator, the 50 arm L¹² associated with such slide will likewise rise and, in doing so, will release its associated pawl L, allowing the latter to rotate in a clockwise direction through a distance determined by the length of the slot L¹⁵ in the comb plate E¹² and, as the pawl is engaged with the rack bar E of next higher order, said rack bar will move rearwardly through a distance of one space to complete the carrying operation.

Thereafter, the accumulator in which carrying 65 has been effected is disengaged from the rack bars E and those rack bars, which were active in carrying, returned to the positions in which they were prior to carrying by the restoration of the slides K¹ to normal position. Such operation will be brought about by the arms L¹² which are depressed by the slides K¹ and which in turn rotate the pawls L in a counterclockwise direction until they are arrested by engaging at the front ends of the slots L¹⁵. Since there was an 70 overthrow movement of the frame members E¹⁷

to effect the engagement of the pawls L with the rack bars E, the first part of the movement of the frame members E¹⁷ in the return direction, will allow the rollers L⁹ on the arms L² to ride off the cam surfaces L⁵, thus allowing the 5 pawls to be withdrawn out of engagement with the rack bars E.

If the rearward movement of the rack bars E is under the control of an accumulator, as in the case of a transfer operation, there is nothing 10 to prevent the additional movement of the rack bars in carrying, since, as described in my Patent No. 2,052,905, previously mentioned, the accumulator from which an amount is transferred is disengaged from the rack bars prior to the disengagement of the accumulator into which the transfer is made. In the event the rearward movement of the rack bars E is controlled from the stop carriage G¹ however, the movement of an additional space to allow carrying in subtraction is permitted by the raising of the interponents K²⁹, as previously stated (see Figs. 4 and 10). These interponents are raised through the medium of the slides K¹ which for this purpose are formed with elongated slots K²⁴ to receive 15 pins K³² provided at the front ends of the arms K³⁰ which carry the interponents. The arrangement is such that, as the slides K¹ rise to effect carrying in subtraction, the interponents K²⁹ will be withdrawn from in front of the stops against 20 which they engage, so that the rack bars E can then move the additional space required in carrying under the control of their associated pawls L, or until the arresting surfaces e on the rack bars 25 engage the raised stops G. Since the width of the interponents K²⁹ is such as to allow a movement of the rack bars of one space, they will, 30 of course, be wide enough to permit the full range of movement of the pawls L (see Fig. 4). It 35 might be mentioned here that when a slide K¹ is depressed to its normal position, the interponent will engage the underlying stop in the carriage, but this will not interfere with the return of the slide K¹ to normal position, since very slight pressure on the stops G will depress 40 them to their normal positions in the carriage.

Prior to the return movement of the rack bars E, an accumulator is engaged for addition and the digit wheels thereof rotated in accordance with the extent of the return movement of the 45 rack bars. The bars however, will not be arrested in their normal positions at the end of the return stroke by the bail J, since prior thereto the bail J is moved forwardly to the position shown in Fig. 7, which is somewhat more than 50 that necessary to permit the rack bars to move the extra space forwardly for carrying in addition. Instead, they are arrested by the engagement of the surfaces e² against bent over ears or lips K²⁶ (see Fig. 8) formed one on each 55 of the slides K¹ and which, in the normal position of the parts, stands in front of the next adjacent rack bar at the left. If during the forward movement of the rack bars, any of the 60 links K have been moved forwardly by the digit 65 wheels of the engaged accumulator, so as to require carrying, the slides K¹ controlled thereby will be released and, when the bail K²⁰ is raised, those slides which are free to move will rise to 70 locate the lips K²⁶ thereon in a position out of the path of the rack bars E, with the result that the corresponding rack bars are allowed to move forwardly one extra space, as determined by the engagement of the rack bars against the cross bar E⁵ (see Fig. 7). 75

When carrying has been completed, the accumulator is disengaged from the rack bars E and the latter thereafter restored to their normal positions by the rearward movement of the bail J, the slides K¹ are depressed by the bail K²⁰, and the active links K cammed back into place by the rotation of the equalizing member K⁶, these operations taking place in the order stated. The ball J, as herein illustrated (see Figs. 3, 4 and 5) is supported by a plurality of arms J¹ rising from a rock shaft J², and its movements are controlled from an edge cam M⁶ mounted on the main shaft M. The intermediate connections include a long fore-and-aft link J³ pivotally connected at its front end to an arm J⁴, likewise pinned to the rock shaft J² at the left, and similarly connected at its rear end to one arm of a bell crank lever J⁵, which is pivotally mounted on the stud K¹² that carries the lever K¹¹. A pull spring J⁶, attached to the link J³, tends to swing the bail J forwardly and maintains an anti-friction roller J⁷ carried by the other arm of the bell crank lever J⁵ constantly engaged with the cam M⁶. As shown in Fig. 3, the cam M⁶ is formed with a high portion M⁷ and a low portion M⁸ and, when the anti-friction roller J⁷ is opposite the high portion of the cam, the ball J, through the lever J⁵ and the link J³, will be retained in its rearward position, whereas when the roller J⁷ is opposite the low portion M⁸ of the cam, the ball J will move forwardly clear of the rack bars E, so that the latter will be free to move the additional space forward to effect carrying in addition, as previously described. When the roller J⁷ again rides up on the high portion M⁷ of the cam, the bail J will engage the surfaces e¹ at the front end of the rack bars and restore them to normal position. It will be observed that the rise in the cam M⁶ occurs before the rise M² in the cam M¹, so that the rack bars E will be restored by the bail before the slides K¹ are depressed. When the extent of rearward movement of the rack bars E is determined by an accumulator, as for instance, in transferring an amount from one accumulator to another, the rack bars, after the accumulator from which the amount is transferred and the pawls L are disengaged respectively from said rack bars in the manner previously described, would move rearwardly out of control, and the settings thus destroyed, so as to forbid transferring to another accumulator by addition in the second phase of the cycle if some means were not provided to prevent such occurrence. Such means in the present machine (see Fig. 1) include a series of pawls O pivotally mounted on a transverse shaft O¹ just above and to the rear of the rack bars E when the latter are in their normal positions. The pawls (which are the same in number as the rack bars) are normally held against the tension of individual springs O² out of engagement with ratchet teeth e⁴ with which the rack bars E are equipped at the top, by a transverse bail O³ standing in front of upwardly projecting fingers O⁴ on said pawls and which is carried by a pair of arms O⁵ pivotally mounted one at each side of the machine on the fixed bar H⁶ which, it will be recalled, supports the auxiliary rack bars H⁸. The bail O³ in turn is held in its normal position, wherein it retains the pawls O out of engagement with the rack bars by a stud O⁶ fixed in the link J³ and projecting in front of the arm O⁵ at the left of the machine (see Figs. 1 and 11). Immediately after the

carrying operation in subtraction occurs however, the roller J⁷ rides off the high portion M⁷ of the cam M⁶ and, as the link J³ moves to locate the ball J in its forward position, the arms O⁵ and the pawl retaining bail O³ will be free to move, allowing the pawls O to effect engagement with the ratchet teeth e⁴ on the rack bars E under the action of their associated springs O². The pawls O are maintained in their active positions during the restoration of those rack bars that have been active in subtraction carrying to the positions in which they were prior to such carrying and until after the rack bars E have started their forward or return movement. Since the setting of the rack bars is maintained in this way, the amount transferred to one accumulator during the first phase of the cycle by subtraction can be transferred during the second phase of the cycle to another accumulator by addition.

During the return movement of the rack bars, the pawls O will merely ride over the ratchet teeth e⁴ and will be returned to their normal positions out of engagement with the rack bars through the rearward movement of the link J³ when it actuates the bail J to return the rack bars to their normal positions after a carrying operation in addition. The restoring movement of the rack bars E is not prevented by the pawls O, since it will be noted that the terminal ratchet tooth on the respective rack bars registers with the corresponding pawl when the rack bars are located in normal position.

In the accompanying drawings, the invention has been shown merely by way of example and in preferred form, and obviously, many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. In a machine of the class described, the combination of a plurality of accumulators, actuating means therefor, and carrying mechanism common to all of said accumulators and operative for both addition and subtraction during one cycle of operation of the machine.

2. In a machine of the class described, the combination of a plurality of accumulators having each a single set of digit wheels, actuating means therefor comprising a single set of rack bars engageable directly with the digit wheels of said accumulators for addition and subtraction, and carrying mechanism common to all of said accumulators.

3. In a machine of the class described, the combination of a plurality of accumulators, each comprising a set of rotatable digit wheels, a single set of reciprocable fore-and-aft rack bars common to said accumulators and movable rearwardly and forwardly during each machine cycle of operation to rotate the wheels of selected accumulators in opposite directions, and means common to corresponding digit wheels of said accumulators and controlled by the rotation thereof to effect carrying for subtraction in one accumulator as the said bars move in one direction, and to effect carrying for addition in another accumulator as the bars move in the opposite direction.

4. In a machine of the class described, the combination of a plurality of accumulators, each

- comprising a set of rotatable digit wheels, means common to all of said accumulators for rotating the digit wheels thereof, and means common to said accumulators and controlled by the rotation 5 of the digit wheels and operable during one phase of a machine cycle to effect carrying in one accumulator for addition, and operable during another phase of the same cycle to effect carrying in another accumulator for subtraction.
- 10 5. In a machine of the class described, the combination of two accumulators, each comprising a set of rotatable digit wheels and selectable one for addition and the other for subtraction, means common to the accumulators for rotating the digit wheels, and common means operable during one machine cycle to effect carrying between adjacent wheels of both accumulators when thus selected.
- 15 6. In a machine of the class described, the combination of a plurality of accumulators, each comprising a set of rotatable digit wheels and selectable each for an operation in addition or subtraction, a set of reciprocable rack bars common to the accumulators for rotating the digit wheels, and carrying mechanism common to all of said accumulators, said mechanism including means operable as the rack bars are moved in one direction to cause carrying between adjacent digit wheels of an accumulator selected for subtraction, and means operable as the said bars are moved in the opposite direction to cause carrying between adjacent digit wheels of another accumulator selected for addition.
- 20 7. The combination as specified in claim 6, characterized by the fact that the carrying mechanism is effective for both the addition and the subtraction operations during one machine cycle.
- 25 8. In a machine of the class described, the combination of a plurality of accumulators, each comprising a set of rotatable digit wheels, common actuating means with which said sets are selectively engageable and adapted during one phase of a machine cycle to rotate the digit wheels thereof in one direction for addition and during a different phase of a machine cycle to rotate the digit wheels thereof in the opposite direction for subtraction, and means common to corresponding digit wheels of the different sets and operable by the wheels of the set engaged to 30 effect a carry-over in addition or subtraction to the adjacent wheel of the said set, depending upon whether the set is engaged for addition or subtraction.
- 35 9. In a machine of the class described, the combination of a plurality of accumulators, each comprising a set of rotatable digit wheels, common actuating means with which said sets are selectively engageable and adapted during one phase of a machine cycle to rotate the digit wheels in one direction for addition and during another phase of a machine cycle to rotate the digit wheels in the opposite direction for subtraction, a common carrying mechanism for the sets functioning both during addition and subtraction, means associated with the digit wheels and operable thereby to control the carrying mechanism, and means for restoring the control mechanism after either an addition or a subtraction carry-over.
- 40 10. In a machine of the class described, the combination of an accumulator having a plurality of rotatable digit wheels, actuating means therefor including a corresponding plurality of rack bars for moving the wheels in one direction for addition and in the opposite direction for subtraction, a control member associated with each digit wheel and movable thereby in one direction for addition and in another direction for subtraction, and means associated with each rack bar and operable upon the movement of the control member associated with an adjacent digit wheel to augment the movement of its associated rack bar to effect a carry-over in addition or subtraction.
- 45 11. In a machine of the class described, the combination of an accumulator having a plurality of rotatable digit wheels, actuating means therefor including a corresponding plurality of rack bars movable through a predetermined number of spaces in one direction for addition and through a predetermined number of spaces in the opposite direction for subtraction, a control member associated with each digit wheel and movable thereby in one direction for addition and in the opposite direction for subtraction, a plurality of devices associated with each rack bar for arresting said bar after movement through said predetermined number of spaces in either direction, and means operable upon the movement of the control member associated with an adjacent digit wheel for operating the arresting devices to permit movement of the rack bar through an additional space in the same direction to permit a carry-over in addition or subtraction.
- 50 12. In a machine of the class described, the combination of a plurality of accumulators having each a set of rotatable digit wheels, common actuating means therefor including a corresponding set of rack bars for rotating the wheels of the accumulators in one direction for addition and in the opposite direction for subtraction, means for arresting the rack bars after a predetermined movement in one direction to enter an amount as represented by such movement into one accumulator, and mechanism operable to permit an additional movement of the rack bars of one space in the same direction for carrying in said accumulator, a set of elements associated one with each of the rack bars (except the first) and operable to restore the rack bars that have been active in carrying to the position in which they were prior to carrying in order to enter the same amount in another accumulator upon movement of the rack bars in the opposite direction, and operating means for said elements.
- 55 13. In a machine of the class described, the combination of a plurality of accumulators having each a set of rotatable digit wheels, common actuating means therefor including a corresponding set of rack bars for rotating the wheels of the accumulators in one direction for addition and in the opposite direction for subtraction, means for arresting the rack bars after a predetermined movement in one direction to enter an amount as represented by such movement into one accumulator, a corresponding set of elements associated one with each of the rack bars (except the first) and operable to permit an additional movement of the rack bars of one space in the same direction for carrying in said accumulator and to effect a restoration of the rack bars that have been active in carrying to the positions in which they were prior to carrying in order to enter the same amount in another accumulator upon movement of the rack bars in the opposite direction, and operating means for said elements.
- 60 14. In a machine of the class described, the combination of a plurality of accumulators hav-

- ing each a set of rotatable digit wheels, common actuating means therefor including a corresponding set of rack bars for rotating the wheels of the accumulators in one direction for addition 5 and in the opposite direction for subtraction, means for arresting the rack bars after a predetermined movement in one direction to enter an amount as represented by such movement into one accumulator, a corresponding set of elements associated one with each of the rack bars (except the first) and operable to permit an additional movement of the rack bars of one space in the same direction for carrying in said 10 accumulator and to effect a restoration of the rack bars that have been active in carrying to the 15 positions in which they were prior to carrying in order to enter the same amount in another accumulator upon movement of the rack bars in the opposite direction, means controlled from the respective digit wheels of next lower order 20 for effecting the operation of said elements in carrying, and means for operating said elements to restore the rack bars after carrying has occurred.
- 25 15. A combination according to claim 14, wherein the set of elements operable in carrying and in restoring the rack bars are controlled during both functions by the same devices.
16. In a machine of the class described, the 30 combination of an accumulator having a plurality of rotatable digit wheels, actuating means therefor including a corresponding plurality of rack bars for moving the wheels in one direction for addition and in the opposite direction for subtraction, a control member associated with each digit wheel and movable thereby in one direction for addition and another direction for subtraction, means associated with each rack bar and operable upon the movement of the control 35 member associated with an adjacent digit wheel to augment the movement of its associated rack bar to effect carrying in addition or subtraction, and an equalizing member for restoring the control members to their medial positions.
- 40 45 17. In a machine of the class described, the combination of a plurality of accumulators having each a set of rotatable digit wheels, common actuating means therefor including a corresponding set of rack bars for rotating the wheels of the 50 accumulators in one direction for addition and in the opposite direction for subtraction, means for arresting the rack bars after a predetermined movement in one direction, and means for retaining the setting of said rack bars as determined

by such movement so as to permit a corresponding movement of said rack bars in the opposite direction.

18. In a machine of the class described, the combination of an accumulator having a plurality of rotatable digit wheels, a corresponding plurality of rack bars engageable therewith, actuating means operating through the rack bars for moving the digit wheels through a predetermined number of spaces in one direction for addition and through a predetermined number of spaces in the opposite direction for subtraction, devices associated with each rack bar and normally retaining said bar against further movement by the actuating means at the end of an 15 operation in addition or subtraction, and control means operable by an adjacent digit wheel for rendering said devices operable to permit said actuating means to move the rack bar an additional space in either direction to effect a carry- 20 over in addition or subtraction.

19. In a machine of the class described, the combination of an accumulator having a plurality of rotatable digit wheels, a corresponding plurality of rack bars engageable therewith, actuating means operating through the rack bars for moving the digit wheels through a predetermined number of spaces in one direction for addition and through a predetermined number of spaces in the opposite direction for subtraction, devices 30 associated with each rack bar and normally retaining said bar against further movement by the actuating means at the end of an operation in addition or subtraction, and a control member associated with each digit wheel and movable 35 thereby in one direction for addition and in the opposite direction for subtraction and adapted when operated to render the devices associated with the rack bar in an adjacent order operable to permit said actuating means to move said bar 40 an additional space in either direction to effect a carry-over in addition or subtraction.

20. In a machine of the class described, the combination of a plurality of accumulators, actuating means, therefor movable during different 45 phases of a machine cycle in different directions from and to normal position, and operable for addition when moving in one direction and for subtraction when moving in the other direction, and carrying mechanism common to all of said 50 accumulators and arranged to operate both for addition and subtraction.

ANSGAR F. STURM.

CERTIFICATE OF CORRECTION.

Patent No. 2,226,451.

December 24, 1940.

ANSGAR F. STURM.

It is hereby certified that error appears in the printed specification of the above numbered patent requiring correction as follows: Page 2, second column, line 61, for "as" read --is--; page 3, first column, line 47, for "bail rod E" read --bail rod E²⁵--; page 4, second column, line 66, for "at" read --as--; page 8, first column, line 45, beginning with "In a machine" strike out all to and including the word and period "direction." in second column, line 3, and insert instead the following as claim 17 -

In a machine of the class described, the combination of an accumulator having a plurality of digit wheels rotatable in one direction for addition and in the opposite direction for subtraction, a corresponding set of rack bars movable in opposite directions for effecting addition and subtraction in said accumulator, a carrying mechanism operable through the rack bars both in addition and subtraction, actuating means for effecting the movement of the rack bars during carrying as well as during addition and subtraction, control members associated one with each digit wheel and movable thereby from an intermediate normal position, in one direction to condition the carrying mechanism for operation in addition and in the opposite direction to condition the carrying mechanism for operation in subtraction, and means for restoring the control members to their intermediate positions.

and that the said Letters Patent should be read with this correction therein that the same may conform to the record of the case in the Patent Office.

Signed and sealed this 4th day of February, A. D. 1941.
